UNITED STATES PATENT OFFICE

2,421,221

LETTER BOX

Walter F. Rothe, Washington, D. C.

Application August 2, 1946, Serial No. 688,132

9 Claims. (Cl. 232—30)

1

The present invention relates to improvements in letter boxes and more particularly to a novel guide adapted to be installed in letter boxes, such as are used by the Post Office Department for the deposit and collection of mail from the street.

Heretofore street letter boxes for post office deposit and collection service are designed, so that the mail deposited therein rests where it drops onto the bottom of the box in scattered confusion. When the collector opens the usual lower collection door of the box this scattered mail must be scraped together by hand and then carried to the mail truck. During this collection of mail and transport thereof to the truck important letters frequently become lost. Accordingly there have been heretofore provided numerous replaceable auxiliary safety receptacles adapted to be attached within the mail box, so that the mail collector may reach in the box through the bottom door and remove the auxiliary container with the deposited mail therein for transfer to his truck without danger of losing individual letters.

The removed container may then be replaced with another similar empty one. However, all such prior arrangements for supporting these containers in the mail box have been clumsy and difficult to use, as the containers, if they be the usual mail bags, must be of a type quickly mounted in the box and released therefrom, while also the bags must be retained open at the mouth to catch the mail as it is dropped in the box.

An object of this invention is to provide a novel mail bag support and guide for the interior of a standard mail box of the deposit and collection type, whereby rapidity of installation of an empty mail bag in open position, and rapidity of removal of the filled or partially filled mail bag from an open to a closed position is facilitated.

Another object is to provide novel guide and bag holding means for attachment to standard type deposit and collection street mail boxes, which novel means is adapted to be sold for installation as an article of manufacture.

A further object is to provide novel locking recesses in the guide means adapted to hold the mail bag in open position.

And still a further object is to provide a flaring portion on the regular guide member for initially receiving and automatically directing the frame of a mail bag into position in the box for holding the mouth of the bag open in the aforementioned locking recesses.

With these and other objects in view, the invention consists in the construction, arrangement and combination of parts hereinafter described

2

and particularly pointed out in the claims, it being understood that I do not intend to limit myself to the details of construction.

In the drawings like parts throughout the several views are given like numerals and are thus identified in the following detailed description:

Figure 1 is a perspective view of the novel bag guides and bag holding means with the bag in place within the mail box, which is shown partly in outline.

Figure 2 is a cross section view of the mail box showing one side of the box.

Figure 3 is another embodiment of my invention showing a fragmentary cross section of the mail box and door and a side view of one of the bag guide members.

Figure 4 is a partial perspective view of the bag and of the rod and roller supports adapted to co-act with the guide members in the sides of the mail box.

Referring in detail to the drawing, there is shown a street-type standard mail box 10 with the usual bottom hinged collection door 11. Mounted on each side 12 and 13 of the box, so as to be visible at the upper part of the collection door opening, are the novel bag guide and bag-holding members of my invention.

One of these members 14 is attached as by braising or welding them to the interior surface of side 12, and the other member 15 is similarly secured or attached to the opposite side 13 of the box 10. As each of the novel members 14 and 15 are made alike a description of one only is necessary. For example, the member 14 comprises an elongated metal channel 16 having at each end a locking means such as the wells or recesses 17 and 18 respectively.

The top elongated surface of each member 14 and 15 slopes downwardly at 19 to shed mail if by chance it should drop thereon.

In this embodiment of my invention the ends of members 14 and 15 are flush against the front and back portions of the mail box, and the supporting rods, hereinafter described of a mail bag 21 are arranged to be directed into the channel 16 of the members 14 and 15 by a downwardly inclined ramp 22. This ramp may be cut out intermediate the ends of each member as an integral part of the members and includes a short roller piloting tongue 24.

The mail bags 21 each are provided with a pair of cross rods 26 and 27 having rollers 28 journaled on each end. These rollers 28 are adapted to coact with the piloting tongue 24 and ramp 22 upon insertion or pushing thereof against the ramp by the mail collector, to thereby auto-

matically direct the rollers upward along the ramp into the channel 16. When the rollers are thus raised to the channel level, the rods 26 and 27 of the bag 10 are spread apart forwardly and rearwardly, until their respective rollers drop into the wells or recesses 17 and 18 at each end of the respective members 14 and 15. Thus the mail bag 10 becomes set and held in open position to receive the mail as it is deposited in the mail box through the usual top letter drop openings, not shown, at the top of the box.

In Figure 3 I have illustrated another embodiment of my invention, wherein the ramp 22 is eliminated and the front end of each member 14 and 15, respectively, is spaced slightly from the front wall of the mail box—a sufficient distance to expose the flared mouth 39 defined by the front recesses 17. This arrangement permits insertion of the guide rollers 28 into the channel 16 of the members at the front of the members at the front of the box. Also in this embodiment in the position of the ramp 22 shown in the first embodiment, I place a recess 31, which is more shallow than the recesses 17 and 18 at each end of the members. The recess 31 functions to temporarily hold the rear rollers on the cross rods which carry the bag and hold the bag partially open to permit the mail collector to give a brief inspection of the contents before final removal of the bag from the box in closed position.

In selecting the mail bags for use with my invention, it is preferable to have bags of a predetermined length, so that when mounted in the mail box the bottom of the bag is held elevated above the interior bottom surfaces of the box. Thus elevated the bag will drain off any moisture from condensation or other causes. Also, as shown in Figure 2 the bag may be perforated in the bottom with brass rings 35 around the openings.

Although only two embodiments of the invention have been illustrated and described in detail, it is to be expressly understood that the invention is not limited thereto. Various changes may be made in the design and arrangement without departing from the spirit and scope of the invention, as will now likely occur to others skilled in the art. For a definition of the limits of the invention, reference should be had to the appended claims.

What I claim is:

1. Means for guiding and holding a mail bag in open position within a mail box, comprising the combination of separable means attached to the open end of the bag, guide channels secured to each opposite interior side wall of the mail box, means projecting downwardly from said guide channels engageable with the said separable means to direct the same into the guide channels, said channels each having recesses defined at each end and to thereby lock the said separable means apart to hold the bag open.

2. Means for guiding and holding a mail bag in open position within a mail box, comprising the combination of separable means attached to the open end of the bag and guide channels secured to each opposite interior side wall of the mail box, said channels each having an integrally struck-out ramp sloping downwardly therefrom to guide the ends of said means upward into the guide channel, and recesses at each end of each channel adapted to receive and hold the separated ends of said means apart.

3. Means for guiding and holding a mail bag in open position within a mail box, comprising

the combination of separable means attached to the open end of the bag and guide channels secured to each opposite interior side wall of the mail box, said channels each having an integrally struck-out ramp sloping downwardly therefrom to guide the ends of said means upward into the guide channel, a pilot member on the end of said ramp adapted to first contact with the ends of said means, and lock means at each end of each channel to receive a separate part of said first-named means.

4. The combination set forth in claim 3, wherein the said separable means comprises a pair of rods secured to a front and back section of the rim of a mail bag, and said rods each having a roller journaled on each end.

5. In a mail box, a pair of guide channels for supporting a mail bag having cross rods at the front and back, said guide channels comprising top and bottom portions, said top portion being sloped inwardly from the inner side of the mail box, and said bottom portion having an intermediate straight flat section leading into a countersunk recess at each end of each channel.

6. In a mail box, a pair of guide channels for supporting a mail bag having cross rods at the front and back, said guide channels comprising top and bottom portions, said top portion being sloped inwardly from the inner side of the mail box, said bottom portion having an intermediate straight flat section leading into a countersunk recess at each end of each channel, a gap intermediate said flat section, and a means extending downwardly from the rear edge of the gap adapted to direct the ends of said cross rods upwardly into the guide channels.

7. In a mail box, a pair of guide channels for supporting a mail bag having cross rods at the front and back, said guide channels comprising top and bottom portions, said top portion being sloped inwardly from the inner side of the mail box, and said bottom portion having an intermediate straight flat section leading into a countersunk recess at each end of each channel, and a recess intermediate the ends of said flat section.

8. In combination with guide channels adapted to be mounted oppositely on each interior side of a mail box, a pair of bag supporting rods, said rods having on each end a roller adapted to engage in one of the said channels, means formed from the channels for guiding the rollers, and means formed in the channels for holding the rods separated at the front and back of a mail box.

9. An article of manufacture for the interior sides of mail boxes, comprising an elongated section of metal, a channel formed in said section to thereby define facing surfaces adapted when installed in a mail box to be in upper and lower horizontal planes, recesses at each end of the channel in the lower of said surfaces, and an inclined member cut out of the lower surface sloping downwardly therefrom.
